Primary Examiner — Cynthia Ramirez*Assistant Examiner* — Michael Maharajh*(74) Attorney, Agent, or Firm* — Terence P. O'Brien(57) **CLAIM**

We claim the ornamental design for a foot pad of an exercise device, as shown and described.

DESCRIPTION

FIG. 1 a side, top perspective view of a foot pad of an exercise device;

FIG. 2 is a first side view of the foot pad of the exercise device of FIG. 1;

FIG. 3 is a second side view of the foot pad of the exercise device of FIG. 1;

FIG. 4 is a close-up, perspective view of the foot pad of the exercise device of FIG. 1; and,

FIG. 5 is a top plan view of the foot pad of the exercise device of FIG. 4.

The ornamental design that is claimed is shown in solid lines in the drawings. The evenly spaced broken lines shown in the figures are for the purpose of showing environment and form no part of the claimed design.

1 Claim, 4 Drawing Sheets---
